PIG CREEP FEEDER

John Quincy Adams, Clark, Mo.

Application June 2, 1955, Serial No. 36,335

Term of patent 14 years

(Cl. D12—2)

Fig. 1.

Fig. 2.

Fig. 3.

Fig. 1 is a perspective view of a pig creep feeder showing my new design,

Fig. 2 is an end view of the same, and

Fig. 3 is a side view of the pig creep feeder.

The undisclosed side and end of the pig creep feeder are substantially the same in appearance as the side and end shown in the drawing.

I claim:

The ornamental design for a pig creep feeder, substantially as shown and described.
